UNITED STATES PATENT OFFICE.

THOMAS EDMUND HOLMES, OF GLASGOW, SCOTLAND.

UNIVERSAL PLATE-ROLLING MILL.

Application filed March 21, 1924. Serial No. 700,852.

To all whom it may concern:

Be it known that I, THOMAS EDMUND HOLMES, a British subject, and a resident of Glasgow, Scotland, have invented certain new and useful Improvements in Connection with Universal Plate-Rolling Mills, of which the following is the specification.

The invention relates to plate-rolling mills of so-called "universal" type—that is to say, 10 mills in which in addition to the usual horizontal rolls operating upon the surface of the plate, there are vertical rolls operating upon its edges. These vertical rolls are laterally adjustable for various widths of plate, 15 and hitherto they have been driven by bevel or equivalent gear, the final pinion of which is fast on or permanently coaxial with the roll. This arrangement has rendered it necessary to provide for the axial adjustment of 20 the next pinion along with the lateral adjustment of the rolls—an arrangement unsound in practice and leading to rapid wear of the gearing. Furthermore, the arrangement limits the size of gear wheels employable, as the lateral distance between centres 25 must coincide with the lateral distance between the rolls' axes, and this is small when narrow plates are being handled.

The invention has for its object to overcome these disabilities.

According to the invention the vertical rolls of mills of this type are each driven by a universally jointed shaft from a vertical shaft above the roll and which is carried in 30 bearings in the housing and is not laterally movable. This vertical shaft is driven by any convenient gearing and either directly or indirectly. Very conveniently, it may be driven by gearing from a vertical shaft lying 35 parallel with it and which in turn is driven by bevel or equivalent gearing from one of the horizontal mill shafts.

The interposition of the universally jointed shaft between the roll and its driving 40 means permits of the driving means to be stationary while the roll is laterally adjust-

ed, and thus obviates the necessity for sliding pinions. Moreover, more particularly when the drive is transmitted through a parallel shaft, it permits of the bevel or 50 equivalent gearing being of any convenient and greater size and strength.

An illustrative example of the invention is shown on two accompanying sheets of explanatory drawings in which Figure 1 is 55 a side elevation of part of a rolling mill and Figure 2 a part view in sectional elevation.

In this example the usual laterally adjustable vertical rolls A arranged as usual adjacently to the horizontal rolls C, are connected by universal joints A¹ to vertical shafts A² which are carried in fixed bearings A³, A⁴ in the housing A⁵. Secured to these shafts are pinions A⁶ which are driven by 60 pinions B secured to vertical shafts B¹ carried in fixed bearings B², B³ in the housing A⁵. To the lower end of these shafts B¹ there are secured bevel wheels B⁴ which 65 gear with and are driven by bevel wheels B⁵ secured to one of the horizontal mill 70 shafts B⁶.

What I claim is:—

In a universal plate rolling mill including a horizontal roll shaft, laterally adjustable vertical rolls, vertical roll shafts, one shaft 75 for each roll, above said rolls, said vertical shafts rotatable in fixed bearings, universal couplings detachably connecting the lower ends of said vertical shafts to the upper ends of said rolls, pinions on said vertical shafts, pinions meshing with the first mentioned pinions, vertical pinion shafts carrying the second mentioned pinions, bevel wheels on 80 said pinion shafts, each bevel pinion located at a level intermediate the upper end of the 85 corresponding roll and the lower end of its roll shaft, and bevel wheels facing one another on said horizontal roll shaft meshing with said first mentioned bevel wheels.

In testimony whereof I have signed my 90 name to this specification.

THOMAS EDMUND HOLMES.
